[57] CLAIM

The ornamental design for a picture image memory unit, substantially as shown and described.

DESCRIPTION

FIG. 1 is a perspective view of a picture image memory unit showing my new design;

FIG. 2 is a front elevational view thereof on a scale smaller than the perspective view of FIG. 1;

FIG. 3 is a top plan view thereof on a scale smaller than the perspective view of FIG. 1;

FIG. 4 is a left side elevational view thereof on a scale smaller than the perspective view of FIG. 1, the opposite side being a mirror image of the side shown; and

FIG. 5 is a rear elevational view thereof on a scale smaller than the perspective view of FIG. 1.
